UNITED STATES PATENT OFFICE.

JACOB FELBEL, OF NEW YORK, N. Y., ASSIGNOR, BY MESNE ASSIGNMENTS, TO UNION TYPEWRITER COMPANY, OF JERSEY CITY, NEW JERSEY, A CORPORATION OF NEW JERSEY.

TYPE-WRITING MACHINE.

1,024,250.

Specification of Letters Patent. Patented Apr. 23, 1912.

Application filed January 26, 1911. Serial No. 604,809.

To all whom it may concern:

Be it known that I, JACOB FELBEL, citizen of the United States, and resident of the borough of Manhattan, city of New York, in the county of New York and State of New York, have invented certain new and useful Improvements in Type-Writing Machines, of which the following is a specification.

10 My invention relates to paper feeding mechanism for typewriting machines and its chief object is to provide improved paper clamping and paper stop devices which are especially adapted for employment in connection with labels and cards and work sheets of like character.

To the above and other ends my invention consists in the features of construction, combinations of devices and arrangements of 20 parts to be hereinafter described and particularly pointed out in the claims.

In carrying out my invention in the present instance, I provide a clamping device preferably made of spring metal, said device 25 extending along the platen and being screwed thereto along one of its longitudinal edges. The clamping device is slotted or cut to provide a set of parallel spring tongues or fingers which curve partly around the platen, 30 transversely thereof. The inherent spring tension of the tongues and of the body of the clamping plate itself causes said tongues normally to press against the platen. A hand controlled rod mounted at its ends on 35 the platen and partly housed in a depression therein is arranged behind the spring tongues and near the roots thereof, said rod being provided with a flattened surface and operating as a cam to swing the tongues 40 away from the platen so that a paper label or a card may be inserted between the platen and the tips of said tongues. A spring mounted stop bar or gaging device is housed 45 in a slot in the platen behind the tips of the spring tongues, the construction being such that when the tongues are cammed away from the platen the stop bar is forced outside the surface of the platen to provide a ledge or stop surface for that edge or end 50 of the label or card first inserted in the machine, this being the bottom edge in the present instance. After the label has been positioned against the landing end or edge

stop the cam rod is actuated to permit the spring tongues to return to the platen and grip the label or substance to be written upon, at the same time forcing the stop bar back within its housing slot. In the present instance, the clamping and stopping devices are adapted to the platen of a front-strike 60 typewriting machine and are arranged on said platen to coöperate with the bottom edge of the label when the same is first inserted, the platen being associated with stops which coöperate to arrest it so that the 65 clamp and stop devices will be in proper position at the front side of the platen to receive the label. Preferably a pressure device of the character shown in the application of Herbert H. Steele No. 530,394, filed 70 November 29th, 1909 is mounted on the platen frame and adapted to coöperate with the label, or other work sheet above the printing line and to hold the same close to the surface of the platen when the platen is 75 turned backward to position the label for receiving the first line of writing, said label being drawn or fed backward by the clamping device as the platen is turned. The pressure device also controls the upper portion 80 of the label as it is line spaced forward.

In a modified construction of my invention herein shown I dispense with the stop bar and arrange the cam rod to serve both as a camming device and as a stop for the 85 paper.

My invention will be more particularly described in connection with the accompanying drawings wherein—

Figure 1 is a fragmentary front elevation 90 of the platen frame and platen of a Monarch typewriting machine embodying my invention. Fig. 2 is a transverse sectional view of said platen and platen frame. Fig. 3 is a fragmentary transverse sectional view showing parts in different relations from those in which they appear in Fig. 2. Fig. 4 is a fragmentary detached face view of the stop bar. Fig. 5 is a view similar to Fig. 3 but showing a modified construction.

Although my invention is shown as applied to a Monarch typewriting machine it will be understood that various features of it may be adapted to other styles of writing machines and that details may be altered when desired or necessary. Further it will

be understood that parts of the regular Monarch machine are omitted in various views, only so much of the machine being shown as is necessary to a clear understanding of my invention.

Referring to Figs. 1 and 2, trackways 1 fixed above the top plate coöperate through anti-friction balls 2 with the slide bar 3 of a platen frame or carrier which further comprises end bars 4. Bearing in said end bars is the axle 5 of a rotary platen which comprises a core 6 and a sheath 7, said axle being provided at its ends with the usual finger wheels 5^a. A platen head 8 is suitably secured to the right-hand end of the platen, while a line spacing ratchet wheel 9 is operatively connected with the left-hand end of said platen. A frame rod or bar 10 is arranged above the platen and is secured 15 at its ends to the end bars 4, said rod 10 providing a support for a pressure device or spring pressed bail like that disclosed in the Steele application aforesaid. Said pressure device comprises a rod 11 extending lengthwise of the platen above the printing line and secured at its ends to arms 12 provided with hubs 13 and finger pieces 14, the hubs bearing on the rod 10 and one of the hubs being connected with a spring 15 coiled 20 around said rod 10 and secured thereto at one end, said spring tending to maintain the pressure rod 11 in coöperation with the platen. The pressure device or bail is not claimed *per se* by me.

35 My novel clamping devices comprise a plate 16 preferably formed of thin sheet metal, the plate extending partly around the platen and curved to conform generally to the surface thereof. Considering the clamp- 40 ing plate to be positioned to receive the label or other work sheet as shown in Figs. 1 and 2, its lower longitudinal edge or end portion is secured to the platen in any suitable way as by wood screws 17. The clamp- 45 ing plate is cut out or slotted transversely as indicated at 18 to provide a set or series of parallel spring tongues or fingers 19 which extend upward transversely of the platen. The inherent spring in the metal 50 composing the clamping plate 16 is such that the tongues 19 will normally engage with the platen surface and coöperate therewith with sufficient pressure to securely hold a paper label, ordinary card or the like.

55 In order to move the spring tongues 19 away from the platen so that the label may be inserted in position to be clamped, a rotary cam, rod or rock shaft 20 is provided, said rod being arranged between the clamp- 60 ing plate and the platen near the roots of the tongues 19 and extending transversely of said tongues and longitudinally of the platen. The left end portion of the rod or shaft 20 is journaled in a lug 21 formed on 65 an annulus 22 which is fixed to the left-

hand end of the platen, said annulus being arranged between the platen end and the line spacing wheel 9 and being preferably of the same diameter as the line spacing wheel. The right-hand end portion of the rod 20 bears in a lug on a circular plate 23 which is fixed by screws 24 to the platen head 8. Preferably the end bearing portions of the rod 20 are reduced in diameter so as to provide shoulders which operate to prevent endwise movement of said rod in its bearings. The right-hand reduced portion of the rod 20 projects outside the plate 23 and carries a crank arm 25 having a hub 26 pinned at 27 to the rod. The crank arm 80 is provided with a laterally projecting handle or finger piece 28 and at the opposite side of its axis is formed with two branches 29 and 30 which serve as stops, coöperating with a stud or stop 31 on the plate 23 to limit the turning movements of the rod 20. Said rod is partly housed in a depression or groove 32 cut in the platen sheath 7 and is cut away at one side as indicated at 33 to provide a flattened surface. When the flat 90 face 33 is turned to face outward toward the tongues 19 as indicated in Fig. 3, said tongues will engage with the platen or the work sheet thereon because of their inherent spring tension. The rod 20 is rotated to the 95 position shown in Fig. 3 by swinging the finger piece 28 until the parts are arrested by the contact of the stop 29 with the stop or stud 31. By pulling the handle 28 in the opposite direction until it is arrested by 100 the engagement of the stop 30 with the stop 31, the rod 20 is rotated on its axis to bring the curved or eccentric-like portion of its surface into engagement with the tongues 19 as shown in Fig. 2. As this curved portion is farther from the axis of rotation than is the flat 33, the rod will in consequence operate to open the clamp, that is, to cam or force the spring tongues away from the platen surface to the position shown in 110 Fig. 2.

Extending longitudinally of the platen, slightly below the free ends or tips of the tongues 19, is a slot or cut-out 34, said slot extending nearly through the platen sheath 7. Near its ends the slot is enlarged to provide holes 35 radial of the platen and which extend through the sheath and part way through the core 6. Arranged in the slot 34 behind the tongues 19 is a stop device or stop bar 36 rectangular in cross section, shown detached in Fig. 4. Said stop bar is provided near its ends with angularly disposed projections or guiding portions 37 which engage in the holes 35. Surrounding the projections 37 and housed within the holes 35 are coiled springs 38 (Fig. 2), said springs tending constantly to force the stop bar 36 outward radially of the platen and to maintain said stop 120 125 130

bar in contact with the backs of the spring tongues 19 near the tips thereof. The spring tension of the tongues, however, normally overcomes the springs 38 and holds the stop bar 36 housed within the platen surface. But when the handle 28 is turned to cam the tongues 19 outward or away from the platen surface as shown in Fig. 3, then the springs 38 will operate to force the stop bar 36 outward to the position shown in said figure, from which it will be observed that the stop bar is thus adapted to serve as a gage against which a label 39, card or the like may be positioned. The portions of the fingers 19 above the stop bar are the gripping or clamping portions, and the depths of these portions may be varied, as by changing the location of the stop bar, according to the character of the work sheet, a heavy work sheet requiring greater depth of clamping surface than a light, thin sheet.

Preferably the platen is positively arrested when it has been turned to bring the clamping and stop devices into initial or receiving position as shown in Fig. 2 by stop devices which in the present instance comprise a radial projection 40 integral with the circular plate 23, said projection coöoperating with a spacing sleeve 41 arranged on the frame rod 10 and between the right-hand end bar 4 and the right-hand collar 13. It will be understood that prior to the insertion of the label 39 the pressure device 11 is swung away more or less from the platen by backward pressure applied to one of the finger pieces 14 and that after the label 39 has been inserted the pressure device is allowed to swing back so that the rod 11 engages the label as shown in Fig. 2.

In some instances it may be more convenient to insert a card or like work sheet by pushing it down between the platen and the rod 11 without first lifting said rod by hand.

After the label or work sheet has been positioned the finger piece 28 is pushed back, swinging the arm 25 rearward and turning the cam rod 20 to bring the flat 33 opposite the clamping fingers 19 as shown in Fig. 5, this movement permitting the fingers to return toward the platen and grip or clamp the lower edge portion of the label 39 as shown in Fig. 3. From this figure it will be observed that the stop bar 36 has been forced inward by the fingers. It will be seen that the stop bar though mounted on the platen independently of the clamping devices or fingers 19 will be at all times under the control of said fingers and that at times movements of said fingers will be transmitted to said stop bar.

After the label 39 has been clamped as described the platen may be turned backward by one of the finger wheels 5 until

the label has been fed backward into position to receive the first line of print. The label or card will be held closely to the surface of the platen by the gripping tongues 19 at one of its edges and by the pressure rod 11 at the opposite side of the printing line, so that thereafter as the label is printed and line spaced forward, it will always lie smoothly and snugly against the platen in the vicinity of the printing line, conducting to clearness or evenness of type impression. The provision of the spring tongues enables the label to be gripped and held more securely than it would be if the clamping device were continuous throughout the length of its clamping edge. Each tongue is in effect a clamp in itself and may operate as such without regard to adjacent tongues. In other words, if the label is short, one or more tongues may operate on it as clamps while the other tongues will be inactive for that purpose. After the writing on the label has been completed it may be unclamped by pulling the finger piece 28 forward, thus enabling the printed label to be removed and a fresh one inserted.

In the modified construction shown in Fig. 5, the stop bar 36 is dispensed with and the cam rod is re-arranged in the space formerly occupied by said stop bar. The relocated cam rod, designated as 42 in Fig. 5, retains all the functions of the cam rod 20 and in addition serves as an end stop device. When the clamping tongues or fingers 19 are opened or moved away from the platen by the cam rod as shown in Fig. 5, the flat 43 of the rod will face upward and will provide an arresting or stop surface against which the lower edge of the label 39 may be adjusted. Afterward the clamp 105 may be closed by rotating the rod 42 as in the prior construction.

Some of the features shown herein are not claimed as they are the invention of Herbert H. Steele and form in part the subject-matter of his application, Serial No. 657,439, filed Oct. 30, 1911.

Various changes besides those specified may be made without departing from my invention.

What I claim as new and desire to secure by Letters Patent, is:—

1. In a typewriting machine, the combination of a platen, a clamp mounted thereon and comprising a plurality of spring tongues supported outside the platen and extending from their support part way around the face of the platen, and a paper stop supported on the platen independently of said clamp and extending transversely of said tongues.

2. In a typewriting machine, the combination of a platen, a clamp mounted thereon and comprising a plurality of spring tongues movable independently of each

- other and of the platen, and a paper stop supported on the platen independently of said clamp.
3. In a typewriting machine, the combination of a platen, a clamping device mounted thereon and pressing normally against the platen, a paper stop separate from said clamp, and means for moving the clamping device away from the platen independently of turning movements of the platen; the paper stop being constructed and arranged to come automatically into operative position when the clamp is moved away from the platen.
15. 4. In a typewriting machine, the combination of a platen, a clamp, means for moving the clamp away from the platen independently of turning movements of the platen, and a stop or gaging device separate from said clamp but constructed and arranged to come automatically into operative position simultaneously with the moving of the clamp away from the platen.
5. In a typewriting machine, the combination of a platen, a clamp which normally presses against the platen, a paper stop or gage movable into and out of operative position, and a cam bar for moving the clamp to inoperative position independently of turning movements of the platen; the paper stop or gage being separate from the clamp but arranged to move into operative position automatically during the camming off of the clamp.
35. 6. In a typewriting machine, the combination of a platen, a clamp mounted thereon and comprising a plurality of spring tongues supported on the outer surface of the platen and extending from their support part way around the platen, and a paper stop supported on the platen independently of said clamp, said clamp being movable relatively to the platen and said paper stop being movable relatively to the platen.
7. In a typewriting machine, the combination of a platen, a clamp mounted on the platen and movable relatively thereto, and a paper stop supported on the platen and movable independently of said clamp, the movements of said paper stop being controlled by said clamp.
8. In a typewriting machine, the combination of a platen, a clamp mounted thereon, hand controlled means for moving the clamp relatively to the platen, and a movable paper stop on the platen, said paper stop being separate from but controlled by said clamp.
60. 9. In a typewriting machine, the combination of a platen, a clamp mounted thereon, hand controlled means for moving the clamp relatively to the platen, a paper stop mounted on the platen, and means for moving the paper stop in one direction. said clamp operating to move the paper stop in the opposite direction.
10. In a typewriting machine, the combination of a platen, a paper clamp, hand controlled means for moving the clamp relatively to the platen, and a spring mounted paper stop on said platen, said paper stop being controlled by said clamp.
11. In a typewriting machine, the combination of a platen, a clamp mounted thereon, hand controlled means for moving the clamp relatively to the platen, a paper stop housed within the platen, and spring means tending constantly to press the paper stop out of the platen, said paper stop being arranged behind said clamp and controllable thereby.
12. In a typewriting machine, the combination of a platen, a clamping device mounted thereon and comprising a series of parallel spring tongues extending transversely of the platen, means for moving said tongues away from the platen, and a spring pressed stop bar housed within the platen behind said tongues and controllable thereby.
13. In a typewriting machine, the combination of a platen, a clamp mounted thereon, hand controlled means for moving the clamp relatively to the platen, a movable paper stop on the platen, said paper stop being separate from but controlled by said clamp, said clamp and said stop being co-operative with the bottom edge portion of a work sheet, and a pressure device co-operative with the work sheet above said clamp and said stop.
14. In a typewriting machine, the combination of a platen frame, a platen, a clamp mounted thereon, hand controlled means for moving the clamp relatively to the platen, a movable paper stop on the platen, said paper stop being separate from but controlled by said clamp, said clamp and said stop being co-operative with the bottom edge portion of a work sheet, and a spring pressed bail mounted on the platen frame and co-operative with the work sheet at the opposite side of the printing line from the clamp and the stop.
15. In a front strike typewriting machine, the combination of a platen frame, a platen, a clamp mounted thereon, hand controlled means for moving the clamp relatively to the platen, a movable paper stop on the platen, said paper stop being separate from but controlled by said clamp, said clamp and said stop being co-operative with the bottom edge portion of a work sheet, a spring pressed bail mounted on the platen frame and co-operative with the work sheet above the clamp and the stop, and a stop for arresting the platen in position to enable the clamp and paper stop to co-operate with the work sheet when it is inserted.
16. In a typewriting machine, a label

clamping device comprising a plate extending longitudinally of the platen and secured along one of its longitudinal edge portions to the platen, said plate comprising a set of parallel spring tongues extending transversely of the platen and curved to conform to the surface thereof, a hand controlled cam for moving said tongues relatively to the platen, and a spring pressed 10 stop bar housed within the platen and arranged behind said spring tongues.

17. In a typewriting machine, a label clamping device comprising a plate extending longitudinally of the platen and secured 15 to the platen along one of its longitudinal edge portions, said plate comprising a set of independently movable parallel spring tongues extending transversely of the platen and curved to conform to the surface there-

of, a hand controlled device for moving said tongues relatively to the platen, a stop bar having angularly disposed guiding portions and being housed within a slot in the platen and arranged longitudinally thereof behind said spring tongues, and coiled springs 25 housed within the platen and coöperative with said guiding portions to press said stop bar radially outward against said spring tongues.

Signed at the borough of Manhattan, city 30 of New York, in the county of New York, and State of New York, this 20th day of January, A. D. 1911.

JACOB FELBEL.
